CLASP

Emma C. Hansen Barnette, Chicago, Ill.

Application May 24, 1938, Serial No. 209,650

3 Claims. (Cl. 24—248)

This invention relates to clasps and more particularly to an improved clasp adapted to be secured to the under surface of the shoulder portion of a woman's garment and arranged to engage and hold in place a shoulder strap.

An object of the invention is to provide a clasp which may be secured to a garment and positioned to be disengageably connected to the shoulder strap.

10 Another object of the invention is to provide a clasp wherein the movable clamping plate is formed of a pair of spring arms coacting with a stationary plate for holding a movable plate in clamping position.

15 A further object of the invention is to provide a clasp for holding the shoulder strap in place wherein the clamping plates have smooth edges or roughened edges.

In the accompanying drawing—

20 Fig. 1 is a perspective view of part of a figure displaying a garment and an embodiment of the invention connected with the garment;

Fig. 2 is an enlarged perspective view of the clasp shown in Fig. 1, the same being shown in 25 connection with part of a garment;

Fig. 3 is an elevation of the clasp shown in Fig. 2 when the same has been moved to its fully open position;

Fig. 4 is a longitudinal central sectional view 30 through the clasp on the line 4—4 of Fig. 5;

Fig. 5 is a top plan view of the clasp shown in Fig. 2 when the same is in functioning position;

Fig. 6 is an end view of the clasp as illustrated in Fig. 4;

35 Fig. 7 is a sectional view similar to Fig. 4 illustrating the end opposite to that shown in Fig. 6;

Fig. 8 is a sectional view similar to Fig. 4 but showing the clasp with smooth clamping edges instead of corrugated edges.

40 Referring to the accompanying drawing by numeral, 1 indicates a garment of any desired kind and 2 a shoulder strap of the kind commonly used by women for supporting certain undergarments.

45 The clasp 3 is adapted to be secured to the garment 1 and the securing means may be of any desired kind, as for instance, a suitable stitching 4, as illustrated in Fig. 4. As illustrated in

50 Fig. 2 the clasp is connected with the garment at the shoulder seam 5 and the stitching 4 extends through only the turned-back edges 6 and 7, but if desired the clasp could be secured to some other part of the garment and also if desired the stitching could extend entirely through

the garment although the arrangement shown in Fig. 2 is considered preferable.

The clasp 3 is provided with a stationary plate 8 held in place on the garment by stitching 4 or other means, and with a movable or clamping plate 9 hingedly connected to the stationary plate 8. It will be noted from Figs. 2 and 3 that the plate 8 is provided with a number of apertures 10 for receiving the thread or stitching 4. The stationary plate 8 is provided with a flat 10 bottom 11 and a pair of upturned edges 12 and 13. These edges are shown as being roughened or scalloped in Figs. 2, 3 and 4, but they could be made smooth as indicated by the numeral 14 in Fig. 8. These edges are adapted to grip the 15 shoulder strap 2, as indicated especially in Fig. 4. At the right-hand end, as shown in Fig. 3, the bottom 11 is provided with a pair of upstanding end members 15 and 16, whereby an opening 17 is left therebetween for receiving the depending extension 18, as shown in Fig. 4. At the end opposite opening 17 there are provided inturned substantially triangular shaped extensions 19 and 20. This end may be termed the hinge end of the plate as the extensions 19 and 25 20 form a combination pintle and cam structure coacting with the curled ends or knuckles 21 and 22 of the movable plate 9. It will be noted that the movable plate 9 is provided with upturned side edges 23 and 24 which are shown as scalloped but they could be made smooth as indicated by the numeral 25 in Fig. 8. The bottom or body 26 of the movable plate 9 is provided with a comparatively large aperture 27 merging into a retracted slot 28, whereby resilient sections 29 30 and 30 are presented. These sections are curled at the ends forming the knuckles 21 and 22, and these knuckles fit over the combined pintle and cam members 19 and 20, as shown in Fig. 3, whereby a resilient action is provided which will 40 hold the movable plate 9 open or fully closed and in clamping action.

When the plate 9 is swung from the position shown in Fig. 3 to the right so that it will assume the position shown in Fig. 4, the sections 45 29 and 30 will yield or spring inwardly and then will move outwardly as the plate 9 moves to its clamping position. In this way there is a constant resilient tension for causing the side edges 23 and 24 to press the shoulder strap 2 against 50 the side edges 12 and 13. This is true whether the side edges are scalloped or smooth.

From Fig. 3 it will also be observed that the body 26 of the movable plate 9 is provided with a short extension which acts as a finger hold 55

whereby the movable member may be readily grasped and swung away from the stationary plate 8. It will also be noted that the stationary plate 8 is secured to the garment 1 and, consequently, if part of the finger or thumb is placed under the extension 31 said extension with the entire movable plate 9 may be swung on its hinge or pivotal mounting so as to release the strap 2. A reverse movement will readily cause the clasp 10 to grip or clamp the strap, as shown in Figs. 1, 4 and 5. It is understood, of course, that the plate 9 is made from resilient material, as for instance metal, and that the upstanding edges 12 and 13 are sufficiently stiff to resist spreading movement when the plate 9 is swung from one position to another.

I claim:

1. A clasp of the character described comprising a stationary plate formed with openings 20 for receiving securing means whereby the plate may be secured to a garment, said plate being provided with a pair of upstanding side walls and a pair of trunnions at one end, said trunnions extending toward each other and constructed to 25 present a pair of cam surfaces, and a movable plate coacting with said stationary plate, said movable plate having a pair of upstanding side edges adapted to pinch an article against the side edges of the stationary plate when the clasp is 30 closed, a pair of resilient sections, and a tubular knuckle on each section, said tubular knuckles fitting over said trunnions, said knuckles being substantially elliptical so that said cam surfaces will

function to resiliently hold the movable member in either of its extreme positions.

2. A clasp of the character described comprising a stationary plate and a movable plate, said stationary plate having at one end a pair 5 of triangular shaped trunnions facing each other, said movable plate having a pair of resilient sections merging at their ends into tubular members which have been flattened to present an almost elliptical opening, said tubular members 10 fitting over said trunnions whereby said movable member is resiliently held in each of two extreme positions.

3. A clasp of the character described comprising a stationary plate adapted to be secured to a 15 garment, said stationary plate being provided with a pair of trunnions facing each other, each trunnion having a substantially A-shaped cam, the cam faces of each cam merging at one point and arranged in a plane parallel to said stationary plate, and a movable clamping plate formed with a body slit from one end toward the opposite end to form a pair of resilient sections, said sections having knuckle members into which said trunnions extend, each of said knuckle members 20 being formed with a substantially elliptical opening with the major axis thereof substantially in a plane parallel with the movable clamping plate so that the portions of the knuckle members may ride on said cam faces as said movable clamping 25 plate is swung from one position to another whereby said movable clamping plate is resiliently held in either of two extreme positions.

EMMA C. HANSEN BARNETTE.
